OSCILLOSCOPE

Neil R. Welsh and Richard E. McCormick, Dana Point,
Calif., assignors to Telonic Industries, Inc., Laguna
Beach, Calif.

Filed July 7, 1969, Ser. No. 18,083

Term of patent 14 years

Int. Cl. D10—10

U.S. Cl. D26—1

FIG. 1

FIG. 2

FIG. 3.

FIG. 4.

FIG. 1 is a perspective view showing the front and right side of the oscilloscope;

FIG. 2 is a top plan view of the oscilloscope of FIG. 1;

FIG. 3 is a perspective view showing the rear and left side of the oscilloscope of FIG. 1; and

FIG. 4 is a bottom plan of the oscilloscope of FIG. 1.

The broken lines are shown for illustrative purposes only and form no part of the claimed design.

We claim:

The ornamental design for an oscilloscope, substantially as shown and described.
